UNITED STATES PATENT OFFICE.

JOHN H. WOODBERRY, OF THE UNITED STATES ARMY.

DETONATING FUSE.

Application filed December 10, 1918. Serial No. 266,144.

(FILED UNDER THE ACT OF MARCH 3, 1883, 22 STAT. L., 625.)

To all whom it may concern:

Be it known that I, JOHN H. WOODBERRY, major, Ordnance Dept., United States Army, a citizen of the United States, stationed at

5 Washington, District of Columbia, have invented an Improvement in Detonating Fuses, of which the following is a specification.

The invention described herein may be 10 used by the Goverment, or any of its officers or employees in prosecution of work for the Government, or by any other person in the United States, without payment of any royalty thereon.

15 In fuses for high explosive projectiles, the explosive elements usually consists of primer, detonator and booster charge, all of which are high explosives. In most fuses the arrangement is such that an explosion of 20 the primer or detonator will produce an explosion of the booster and consequently the shell, and unless special safety means are provided for separating the detonator from the booster, an accidental explosion of the 25 shell may result, in storage, transportation or while it is in flight in the bore of the gun, through a premature explosion of the detonating elements which are of a highly sensitive nature.

30 My invention is designed to provide safety means for separating the detonating elements from the booster elements by means hereinafter described.

It is well known to those skilled in the art 35 that while the projectile is passing through the bore of the gun in flight the component parts are subjected to forces due to linear acceleration and angular velocity.

40 My invention resides in the utilization of a component part of the forces due to linear acceleration to overcome centrifugal force on a safety member included in the safety mechanism.

The embodiments of my invention as illustrated in the accompanying drawings show 45 simple means for utilizing this principle for the purpose described, but to those skilled in the art, other embodiments are apparent.

Another object of my invention is to provide means whereby the fuse is armed after 50 the projectile has left the bore of the gun and the safety device has performed its function.

Another object of the invention is to pro-

vide means for utilizing this safety means 55 for holding separate the sensitive detonating elements from the booster charge until after the projectile leaves the gun.

Other objects and advantages will be apparent as the description proceeds. 60

The accompanying drawings disclose illustrative embodiments capable of carrying out the underlying principles of the invention. Like reference characters indicate corresponding parts throughout the several 65 views. The several figures of the drawing may be briefly described as follows:

Fig. 1 is a central longitudinal vertical section of a fuse showing one embodiment of my invention. 70

Figs. 2 and 3 are transverse sectional views on the lines 2—2 and 3—3, respectively.

Fig. 4 is a collective perspective detail view of two units of my composite safety locking device. 75

Fig. 5 is a longitudinal section taken on the line 5—5 of Fig. 6.

Figs. 6 and 7 are transverse sectional views on lines 6—6 and 7—7, respectively, of Fig. 5. 80

Fig. 8 is a force diagram.

Referring, now, more in detail to the drawings:

The fuse body of the fuse shown in Fig. 1, comprises an elongated cylindrical casing 1, 85 having a rear enlargement 1^a, and a fuse stock 2 screwed on to the said enlargement 1^a as shown. The fuse stock is provided with a rear extension 2^c of reduced diameter and screws into the shell casing A. Secured in the rear open end of said extension is an elongated cup 10, the mouth thereof communicating with the chamber of the extension 2^c. The extension 2^c, and the cup 10 constitutes the booster casing. 95

The plunger 6 is mounted for rectilinear sliding movement in said fuse stock 2 and for this purpose is guided in its movements by an annular flange 2^a and by a flange 2^b in the rear of flange 2^a. Between flanges 2^a and 2^b is an air-chamber 21, surrounding the plunger 6, which communicates through radial openings 22 in the fuse stock, with the outside atmosphere. 100

The forward face of the flange 2^a is inclined in a direction oblique to the axis of the plunger 6 and to the fuse stock 2, as shown at 17, and this oblique face constitutes

a seat for safety locking members 16, more particularly hereinafter to be described.

In front of the flange 2^a, the fuse stock is provided with radial openings 2^b, by 5 which the air chamber 2^d in front of said flange 2^a may communicate with the outside atmosphere.

The plunger 6 is provided with a forward projecting hollow extension 6^a, and adjacent to the rear end of said extension the plunger is provided with a circumferential groove or recess 18, for a purpose presently appearing. The plunger is also provided with a peripheral pocket 19, which, in the 15 normally locked position of the plunger, is in alignment with the air chamber 21 as shown.

Secured to the rear end of the flange 2^b is an elongated cup 9 disposed in the extension 2^a. The cup carries, at its rear or closed end, a firing pin 8 cooperable with the firing cap 7. The firing cap is carried in the rear of the plunger 6 and is connected by a port 20 with the annular groove 19, 25 which carries the detonating material. Closing the pocket 19 is a sleeve 19^a enclosing the plunger 6.

The plunger extension 6^a is provided, at its forward end, with a head 3 secured to 30 said extension by a shear pin 5.

To render the fuse safe during transportation and storage, there is provided a loose locking collar 11, which is, by a shear pin 12, held rigidly on the casing 1, adjacent 35 to but spaced from the enlargement 1^a. When the sleeve is in the normal position, as shown by Fig. 1, it bears on the spherical locking member 13 in the recess 14 of the extension 6^a and in an aligned aperture 15 40 of the casing 1. This arrangement locks the plunger extension 6^a to the fuse casing and also binds the locking members 16 against the oblique seat 17 and against the shoulder defining the front terminus of the groove 18, 45 preventing said members from becoming separated by a lateral shock during transportation.

The plunger 6 is permitted to move rearwardly to armed position only through the 50 action of the locking members 16, which do not move from the position shown in Fig. 1, upon firing, until linear acceleration of the projectile ceases. At this instant which occurs shortly after the projectile 55 leaves the bore, centrifugal force on these members, being no longer opposed, moves them outward, disengaging the plunger 6. This composite locking device is composed of a plurality of sectors (four being shown 60 in this instance), having an inclined face 16^a which fits the frusto-conical surface 17 in the front face of the flange 2^a. The shape of these sectors is clearly shown in Fig. 4, and it will be noted that they are normally 65 seated in the peripheral recess 18 and are

arranged symmetrically around the plunger 6. Consequently, by the construction described, in order to release the plunger, the sectors must move radially and also axially forward.

The operation may be briefly described as follows:

On firing the projectile the safety members 16, while in the bore are subjected to forces due to linear acceleration and rotation. Diagrammatic representation of these forces is shown in Fig. 8, in which *o* is the center of gravity of one of the locking members. The vector *L*, represents the force acting on this part due to linear acceleration. Vector *R* represents the centrifugal force acting on this part. The vectors *s* and *c* represent respectively the components of these forces in a direction parallel to the seat on which the member is constrained to move.

In designing the fuse the angle of inclination *A* is so chosen that the component *s* will always be greater than the component *c* while the projectile is traveling in the bore. This condition therefore prevents outward movement of the locking members; however, when the projectile leaves the bore of the gun the vector *L* ceases to exist and the component *c* imparts an outward motion 95 to the locking members 16. After the locking members 16 have moved outward sufficiently to disengage shoulder 6^b, the plunger 6 is free to move rearward.

Air resistance on the head 3 of the plunger 6 now causes the plunger to move rearwardly to the dotted line position shown in Fig. 1, the movement being limited by the shear pin 5 which contacts with the end of the casing 1. This movement takes the detonator 19 from the safety chamber 21 through the firing pin cup where it is in contact with the booster charge. Upon impact of the head 3 with the target, or the like, the pin 5 is severed and the plunger moves farther rearward, bringing the primer 7 into contact with the firing pin 8, thus exploding the detonator 9, which detonates the booster charge, and causes the detonation of the main body of the high explosive material.

Before firing the fuse the detonator 19 is surrounded by air-chamber 21 and the lower part of this chamber is closed by the metal end of plunger 6. In this position should the detonator 19 be accidentally exploded detonating wave will not be transmitted to the booster charge and therefore the shell will not be exploded, since the air-chamber serves to reduce the force of the explosion of the detonator 19. Should it be desirable to further reduce the effects of the accidental explosion, vents 22 may be utilized for connecting the air-chambers with the atmosphere.

Fig. 5 illustrates a modification of my device in which the centrifugal locking members 16^b are shown used in connection with a standard time fuse rather than with a sensitive percussion operated fuse. This modification is merely illustrated to show that the principle of the two opposing forces of linear acceleration and angular velocity may be utilized in fuses of various designs. This 10 modification also shows a safety chamber 21^b similar in its function to the safety chamber in Fig. 1. In this design the safety chamber is located within the shell and therefore it is necessary to incline the vent 15 holes 22^b corresponding with the vent hole 22 of Fig. 1. The reference character 12^b represents a centrifugal lug for locking the plunger 6^b against the safety members 16^b, thus preventing accidental displacement. 20 When the locking members 16^b disengage the plunger 6^b the fuse is armed. Upon the explosion of the base charge of the time fuse either by time action or impact, the plunger 6^b is driven violently rearward from 25 the safety position to the firing position and against the firing pin 8^b. This causes the detonation of the shell.

While I have, in compliance with the letter and spirit of the patent laws, described, 30 with great particularity, several specific structural embodiments of my invention capable of carrying out the underlying principles thereof, it is to be understood that various changes will suggest themselves to 35 those skilled in the art to which the invention appertains, and that all of such modifications as come within the scope of the appended claims constitute no departure from my invention.

40 Having thus fully described my invention, what I claim as new, and desire to secure by Letters Patent is:

1. The combination with a fuse for projectiles, of a plunger detonator movable longitudinally of the fuse, a centrifugally movable locking member controlling the functioning of the fuse, said member lying on a surface oblique to the longitudinal axis of rotation of the projectile, the obliquity of 50 said surface and the inertia of said member and of the plunger being effective to prevent the member from moving centrifugally during the acceleration period of the projectile in the bore of the gun.

55 2. The combination with a fuse for projectiles, of a plunger detonator moving from a non-functioning to a functioning position, a centrifugally movable locking device deterring the movement of said plunger to 60 functioning position, said device lying on a surface oblique to the axis of rotation of the projectile, the obliquity of said surface and the inertia of said device and said plunger being effective to prevent said device from 65 moving centrifugally during the accelera-

tion period of the projectile in the bore of the gun.

3. The combination with a fuse for projectiles, of a plunger detonator movable from a non-functioning to a functioning position, and a centrifugally movable locking device deterring the movement of said plunger to functioning position, said device lying on a surface oblique to the axis of rotation of the projectile and normally locked against movement by said plunger. 75

4. In a fuse for projectiles, the combination, with a plunger detonator having a recess providing an annular shoulder lying in a plane substantially at right angles to the longitudinal axis of the plunger, of safety means normally engaging said recess and contacted by said shoulder and moved in a direction oblique to the axis of said plunger to release the same. 85

5. In a fuse for projectiles, the combination, with a plunger detonator having a circumferential recess providing a shoulder lying in a plane substantially at right angles to the longitudinal axis of the plunger, and a composite safety device normally engaging said recess and movable in a direction oblique to the axis of said plunger to release the same. 90

6. In a fuse for projectiles, the combination, with a detonating plunger, of safety locking means normally engaging said plunger and centrifugally movable in a direction oblique to the axis thereof, to release the same, and an auxiliary locking device also normally engaging said plunger for preventing accidental release movement of said safety locking means. 100

7. In a fuse embodying a casing, a plunger-detoner, safety locking mechanism, 105 normally engageable with said plunger-detoner to hold the same in unarmed relation, and centrifugally movable to releasing position, and a member normally locking said plunger-detoner to the fuse casing and preventing tendency to movement of 110 said locking mechanism to releasing position, due to any lateral shock.

8. In a fuse embodying a casing, a plunger-detoner, safety locking mechanism, 115 normally engageable with said plunger-detoner to hold the same in unarmed relation, and centrifugally movable to releasing position, and a member normally locking said plunger-detoner to the fuse casing and preventing tendency to movement of 120 said locking mechanism to releasing position, due to any lateral shock, and means for maintaining the member against accidental displacement. 125

9. In a fuse embodying a casing, a plunger-detoner, safety locking mechanism, 130 normally engageable with said plunger-detoner to hold the same in unarmed relation, and centrifugally movable to releasing

position, and a spherical body normally locking said plunger-detoner to the fuse casing and preventing tendency to movement of said locking mechanism to releasing position, due to any lateral shock, and a collar encircling said casing, and bearing against said spherical body, for retaining the latter against accidental displacement.

10. In a fuse embodying a casing, a plunger-detoner, safety locking mechanism normally engageable with said plunger-detoner to hold the same in unarmed relation, and centrifugally movable to releasing position, and a spherical body normally locking said plunger-detoner to the fuse casing and preventing tendency to movement of said locking mechanism to releasing position, due to any lateral shock, and a collar encircling said casing and bearing against said spherical body for retaining the latter against accidental displacement, and means for yieldingly retaining said collar against accidental displacement.

11. In a fuse embodying a casing, a plunger-detoner, safety locking mechanism normally engageable with said plunger-detoner to hold the same in unarmed relation, and centrifugally movable to releasing position, and a body normally locking said plunger-detoner to the fuse casing and preventing tendency to movement of said locking mechanism to releasing position, due to any lateral shock, and a collar encircling said casing and bearing against said body for retaining the latter against accidental displacement, and a shear pin for yieldingly retaining said collar against accidental displacement.

12. In a fuse embodying a casing, a plunger-detoner, safety locking mechanism normally engageable with said plunger-detoner to hold the same in unarmed rela-

tion and centrifugally movable to releasing position, means for locking said plunger-detoner to the fuse casing and preventing tendency to movement of said locking mechanism to releasing position, due to any lateral shock imparted to the latter, and means for limiting the rearward movement of said plunger-detoner under impact therewith of air, when said locking means and said centrifugally operable locking means move to releasing position.

13. In a fuse embodying a casing, a plunger-detoner, safety locking mechanism normally engageable with said plunger-detoner to hold the same in unarmed relation and centrifugally movable to releasing position, means for locking said plunger-detoner to the fuse casing and preventing a tendency to movement of said locking means to releasing position due to any lateral shock imparted to the latter, and a pin carried by said plunger-detoner and impinging against said casing to limit rearward movement of said plunger under impact therewith of air, when said locking means and said centrifugally operable locking means move to releasing position.

14. In a fuse, the combination with a fuse casing, of a fuse stock connected with said casing, a plunger detonator movable axially of said fuse stock, a forwardly extending projection carried by said plunger and projecting beyond the forward end of said fuse casing, locking means in said fuse stock and normally engaging said plunger to maintain the same in the forward position in the said fuse stock, and separate locking means normally locking said plunger extension to said fuse casing and preventing accidental releasing movement of said locking mechanism.

JOHN H. WOODBERRY.
